CARRIER

Raymond P. Packard, Tacoma, Wash.

Application March 6, 1946, Serial No. 652,369

4 Claims. (Cl. 224—45)

1

This invention relates to a carrier for sheet material of which a typical example is a plywood panel. However, the carrier of this invention is not limited to such use and the same may be utilized in all fields where like problems exist in whole or in part.

Heretofore in handling large sheets, such as plywood panels of four-foot width and eight-foot height, it required two men to move the panels from place to place or to secure the panels in place to form a surface of a wall. The need for two men was not necessitated by the weight of the panels involved but was necessitated because of the dimensions thereof and the inherent difficulty of handling articles of such dimensions. It is an object of this invention to provide a carrier having a trough-like member which may be positioned below the sheet to be carried and having a handle in spaced relation to the trough-like member so that the sheet can be carried at a suitable position vertically considered.

It is a further object of the invention to provide a handle means suitably laterally spaced in relation to the sheet being carried to protect the hand of the worker carrying the sheet.

It is a further object of the invention to provide a carrier device wherein the trough-like member which engages below the sheet to be carried is pivotally connected to the carrier member so that the sheet may be angularly moved and remain in balance even when the sheet is being carried up or down an elevation, such as a flight of stairs.

It is a further object of the invention to provide a carrying device so that a worker can move a panel to a position such as that where it will form the surface of a wall, and which device permits the worker to hold the device and the carried panel in position by his knee which will thus permit the worker to have both hands free to square and fasten the panel on the studs or furring strips of a wall construction.

The above mentioned general objects of my invention, together with others inherent in the same, are attained by the mechanism illustrated in the following drawings, the same being a preferred exemplary form of embodiment of my invention, throughout which drawings like reference numerals indicate like parts:

Figure 1 is a view in elevation of a device embodying this invention;

Fig. 2 is a view in side elevation of the same looking in the direction of broken line 2—2 of Fig. 1;

Fig. 3 is a top plan view of the same; and

2

Fig. 4 is a view in elevation, on a smaller scale than the previous figures, showing a panel in place on the carrier and a position which the parts of the carrier and a panel may assume as a panel is being carried up an elevation, such as a flight of stairs indicated by dot and dash lines.

Referring to the drawings a trough-like panel receiving means 5 has a base portion 6 and two legs portions 7 and 8. The leg portion 7 is preferably shorter than the leg portion 8 so that the leg portion 7 can readily be inserted below a panel and so the leg portion 8 can function as a supporting means. The base portion 6 will be of a contour and shape to interfit with the articles to be carried and if such articles are rectangular sheets, then the base portion 6 will be flat as shown. Also, the spacing between members 7 and 8 will be such as to permit insertion therebetween of the thickest panel to be carried.

The trough-like panel receiving means 5 is pivotally supported and this may be accomplished by providing a link means 9 pivotally secured to the leg portion 8 by pivot means 10. A handle means 11 is secured in vertical spaced relation to the trough-like panel receiving means 5 by suitable frame means which preferably comprises the link means 9 and a bail having vertical leg portions 12 and a horizontal portion 13. The link means 9 is preferably bent as shown in Fig. 2 to provide a horizontal portion 14. The horizontal portion 14 is provided with spaced perforations through which the leg portions 12 of the bail may be inserted and thereafter the said leg portions can be bent as best shown in Fig. 1 to provide security of the leg portions 12 of the bail to the link means 9. Before bending of the bail to provide both leg portions 12 and securing the leg portions 12 to the link means 9, a handle means 11 can be suitably threaded on the portion 13 of the bail and thus a light and inexpensive frame means is provided to support the handle means 11 and which is pivotally secured to the trough-like panel receiving means 5.

A handle guard 15 is provided to maintain carried panels in spaced relation to the handle means 11. This handle guard is preferably in the form of a U-shaped yoke having legs 16 and a plate member 17. The legs 16 can be bent at their free ends and thereby secured to the leg portions 12 of the bail.

Referring now to Fig. 4 of the drawings, a panel 18 will have its lower edge supported by the trough-like panel receiving means 5 and the panel when carried will have a surface abutting against the plate member 17 of the handle guard 15.

Thus the panel 18 will be in spaced relation to the handle 11 and thus a workman's hand will be protected when carrying a panel and having his hand engage the handle means 11. The trough-like panel receiving means 5 will be positioned relative to the width of the panel being carried so that the weight will be at balance about pivot means 10. The workman can use one hand on handle 11 and his other hand on the top of the panel. The distance between handle 11 and the trough-like panel receiving means 5 is such as to permit the average workman to walk erect and still have the lower edge of the panel in working spaced relation to a floor.

As the workman carries a panel up or down an elevation, such as a flight of stairs 19 of Fig. 4, he can angularly move the panel and dispose the same in the position shown in Fig. 4 of the drawings and thus a balance of the weight of the panel may be maintained about pivot means 10 regardless of whether a panel is being carried on a level or up or down an elevation.

Another important field of use of my invention which inheres in its construction is that of applying panels in place to form a wall surface. When panels as plywood panels or the like are employed in forming a wall surface, generally these panels are of the height of the wall to be formed less a space at the bottom which will be covered by the usual trim. Thus a workman in securing such panels in place is required to handle a panel of a length of approximately 8 feet and to hold the top of the panel tightly against an upper abutment and the sides against an adjacent panel and at the same time to nail the panel in place to hold it in the aligned position. Heretofore it was not possible for a single workman to align and secure panels in place as he did not have enough hands. With my device the workman can lift the panel in place while engaging the handle 11. The studs or furring strips to which the panels are to be secured will be to the right relative to the device as shown in Fig. 2 of the drawings. There is an opening between the legs 16 of the handle guard 15 and between the leg portions 12 of the bail. Thus a workman can insert his knee in this opening and lift his knee to engage handle means 11 and thus a panel can be held in place with the top of the panel in the proper elevation and with a side of a panel abutting the side of an adjacent panel or abutting studs or the like and the workman will have both hands free to provide for aligning the panel and applying the securing means or nails.

It is thus obvious that I have provided a construction of extreme lightness in weight so as not to increase the load to be carried by the workman and a device of rigid construction and of extreme utility in carrying sheet materials of large dimensions.

Obviously, changes may be made in the forms, dimensions, and arrangement of the parts of my invention, without departing from the principle

thereof, the above setting forth only a preferred form of embodiment.

I claim:

- 5 1. In a device of the class described, frame means; a trough-like panel receiving means pivotally connected with the lower end portion of said frame means and extending to one side thereof; handle means connected with the upper end portion of said frame means; and a yoke-like handle guard means connected with the upper portion of said frame means and extending to the said one side thereof.
- 10 2. In a device of the class described, a bail; link means interconnecting the leg portions of said bail at their lower end portions; a trough-like panel receiving means pivotally connected with said link means and extending to one side of said link means and said bail; handle means carried by the top portion of said bail which interconnects the leg portions; and a handle guard means connected with the top portions of the leg portions of said bail and extending to the said one side thereof.
- 15 3. In a device of the class described, a bail; link means interconnecting the leg portions of said bail at their lower end portions; a trough-like panel receiving means pivotally connected with said link means and extending to one side of said link means and said bail; handle means carried by the top portion of said bail which interconnects the leg portions; and a yoke-like handle guard means connected with the top portions of the leg portions of said bail and extending to the said one side thereof.
- 20 4. In a device of the class described, frame means; a trough-like panel receiving means pivotally connected with the lower end portion of said frame means for movement in a plane substantially parallel to said frame means and extending to one side thereof, whereby a panel may be angularly moved to adjust its center of mass for carriage on level or on inclined supports; handle means connected with the upper end portion of said frame means; and a handle guard means connected with the upper portion of said frame means and extending to the said one side thereof for supporting the top portion of a panel against angular movement toward the handle means.

Certificate of Correction

Patent No. 2,428,941.

October 14, 1947.

RAYMOND P. PACKARD

It is hereby certified that error appears in the printed specification of the above numbered patent requiring correction as follows: Column 4, line 9, claim 1, after "means" insert *and disposed in vertically spaced relation to the trough-like panel receiving means a distance substantially equal to a person's lower leg so that the handle means may be supported by one's knee*; and that the said Letters Patent should be read with this correction therein that the same may conform to the record of the case in the Patent Office.

Signed and sealed this 16th day of December, A. D. 1947.
